UNITED STATES PATENT OFFICE.

ERVIN E. ROBERTS, OF SAN DIEGO, CALIFORNIA.

AIR BUOY FOR BATHERS AND THE LIKE.

Application filed June 11, 1925. Serial No. 36,300.

My invention relates to air buoys to be used for emergency purposes on boats and by bathers in the water and for beginners in learning to swim and the objects of my invention are:

First, to provide a buoy of this class which may be readily connected inside of a bathing suit or the clothing of an individual. Second, to provide a buoy of this class which may be readily filled with air if desired, by blowing through a valve structure. Third, to provide a valve for buoys of this class by which an individual may readily fill the buoy by blowing into it and which may be emptied by operating a plunger in the valve. Fourth, to provide a buoy of this class which provides an audible sound to attract attention when it is being filled with air. Fifth, to provide a novelly constructed valve for air buoys. Sixth, to provide a novelly constructed air buoy and seventh, to provide an air buoy and valve of this class which is very simple and economical of construction, durable, efficient, reliable and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a side elevational view of my air buoy in deflated form. Fig. 2 is a fragmentary longitudinal sectional view through 2-2 of Fig. 1 on an enlarged scale. Fig. 3 is a fragmentary sectional view on an enlarged scale through 3-3 of Fig. 1. Fig. 4 is a similar view through 4-4 of Fig. 1. Fig. 5 is a top view on an enlarged scale, showing the buoy body portion fragmentarily and Fig. 6 is a sectional view on an enlarged scale through 6-6 of Fig. 1.

Similar characters of reference refer to similar parts and portions throughout the several views of the drawings.

The main body member 1, tabs 2 and 3, valve member 4, valve diaphragm member 5 and valve plunger 6, constitute the principal parts and portions of my air buoy.

The main body member 1 is preferably composed of flexible rubber in sheet form

and bag shaped as shown best in Fig. 1 of the drawings, the Fig. 1 being practically flat and before being filled with air. It is overlapped at the back side at 1^a and provided with cement 1^b, thus providing an air and water tight seam. It is provided along its curved side with cement 1^c, shown best in Fig. 2 of the drawings and sewed together by means of thread 1^d. Mounted at 65 the lower opposite sides are a pair of tabs 2 which extend downwardly and fold backwardly, as shown best in Fig. 3 of the drawings and provided with cement 1^e between the fold and body portion. It is also provided intermediate its ends with oppositely disposed tabs 3 which are composed of flexible rubber, the same as the body and folded against itself and sewed at 3^a, shown best in Fig. 4 of the drawings and cemented over 70 the edges by means of cement 3^b and 3^c. The upper end comes to nearly a point and is provided with an opening in which is inserted the one end of the valve member 4 which is provided with a groove 4^a near its 75 lower end with an outward flange 4^b intermediate its ends and its upper end with an enlarged portion 4^c. It is provided with a central hole 4^d which is provided with an enlarged opening 4^e at one end and 4^f at 80 its opposite end. This member 4 is also provided with a V-shaped cut away portion 4^g at opposite sides, shown best in Fig. 6 of the drawings.

Mounted over the end of this member 4 is a rubber diaphragm member 5 which is of sufficient width to cover the opening 4^e and extends part way over the grooves 4^g. It is held in position by means of a band 5^a, which clamps the member 5 into the 95 grooves 4^a. Mounted over this lower end and over the extended portions of the portion 5 at the upper end is the body 1 secured in position by means of a string 1^e.

The operation of the device is as follows:

The deflated buoy is positioned inside of the bathing suit or other garment of the wearer with the portion from the tabs upwardly folded back against the other portion of the body, the tabs 2 and 3 are secured to the inside of the bathing suit or other garment, the tabs 3 being near the neck portion; then in case of emergency or necessity for use, the wearer can reach the folded portion, draw it out and by blowing 110 into the upper end of the member 4 can inflate the buoy as desired, the air will

pass inwardly through the orifice 4^a, expand the rubber diaphragm 5 so that the air passes into the body of the air buoy and the air will hold the diaphragm against the opening 4^e and prevent the air from being released.

It will be here noted that the plunger 6 is provided with an enlarged portion 6^a, the opposite portion of which is adapted to engage the portion 4^b of the member 4 and form an additional seal as this plunger extends slightly below the lower end of the member 4 as shown best in Fig. 2 of the drawings. If it is desired to release the air or any portion thereof, from the body of the buoy it can be done by depressing the plunger 6 sufficiently to let the air out.

It will be noted that when blowing into the member 4, the air will pass by the corners of the grooves 4^c causing an audible signal when the buoy is being filled.

Though I have shown and described a particular construction, combination and arrangement of parts and portions, I do not wish to be limited to this particular construction, combination and arrangement but desire to include in the scope of my invention the construction, combination and arrangement substantially as set forth in the appended claims.

Having thus described my invention, what I claim as new and desire to secure by Letters Patent is:

1. In an air buoy of the class described, a flexible hollow rubber member provided with tabs secured thereto adapted to be secured to a garment, an air check valve secured in the one end thereof comprising a valve member provided with an orifice therethrough secured in said body member,

an elastic diaphragm member secured thereto and extending over the lower end of said orifice and a plunger mounted in the orifice in said valve member.

2. In an air buoy of the class described, a rubber bag provided with an orifice in one end, a plurality of tabs secured thereto, a check valve secured in the orifice in said bag comprising a valve member provided with an orifice therethrough secured in said body member, an elastic diaphragm member secured thereto and extending over the lower end of said orifice and a plunger mounted in the orifice in said valve member.

3. In an air buoy of the class described, a flexible bag provided with an orifice therein, a valve member secured therein and provided with an opening therethrough provided with an enlarged portion at opposite ends, the inner end forming a valve seat, a plunger reciprocably mounted in said opening provided with an enlarged end forming a valve member for engaging said valve seat, a diaphragm mounted over the end of said valve member adapted to close the opening therein.

4. In a device of the class described, a valve member provided with an opening therethrough provided with an enlarged portion at opposite ends, the inner end forming a valve seat, a plunger reciprocably mounted in said opening provided with an enlarged end forming a valve member for engaging said valve seat and a diaphragm mounted over the end of said valve member adapted to close the opening therein.

In testimony whereof, I have hereunto set my hand at Los Angeles, California this 3d day of June 1925.

ERVIN E. ROBERTS.
